PRODUCTION OF TERPENES

Edward Frank Wadley, Baytown, Tex., assignor
to Standard Oil Development Company, a cor-
poration of Delaware

Application December 13, 1943, Serial No. 514,012

4 Claims. (Cl. 260—675.5)

The present invention is directed to a method for producing terpene type hydrocarbons. More particularly, it is concerned with a process which includes a combination of catalytic cracking and treating steps whereby alicyclics and terpene hydrocarbons are obtained in substantial quantities.

The presence of terpene hydrocarbons in petroleum fractions has long been suspected by numerous investigators, but none of them has ever demonstrated satisfactorily that these hydrocarbons are actually present in natural petroleum. The presence of terpene hydrocarbons in thermally cracked products has likewise been suspected and efforts have been made to segregate the terpene compounds. However, all of the early investigations reported in the literature have met with little success. It has never been demonstrated to any satisfaction whether the suspected presence of these terpene hydrocarbons was due to the effect of thermal conditions on the petroleum fraction or whether it was due to the subsequent treatment with chemicals such as sulfuric acid and alkaline reagents. In general, the literature is uncertain as to the actual presence or formation of terpene hydrocarbons in petroleum distillates.

These terpene hydrocarbons are found occurring naturally in substantial quantities in the conifers and a large industry has sprung up to recover and exploit these naturally occurring compounds of vegetable origin.

I have now discovered that a substantial quantity of terpene hydrocarbons may be produced and recovered from a catalytically cracked naphtha. This discovery is of paramount importance since it makes available large quantities of terpene hydrocarbons which heretofore were only obtained from the conifers, specifically the pines, at the expense of tedious labor and destruction of the pine forests.

I have found that these terpene hydrocarbons may be obtained by subjecting a paraffinic or naphthenic gas oil to conditions of catalytic cracking whereby gasoline and heavier hydrocarbons are produced. The light gasoline fraction boiling below about 250° F. is then subjected to treatment with a chemical reagent such as by treatment with a strong mineral acid, specifically sulfuric acid, followed by distillation to recover a fraction rich in the terpenes.

In general, my invention comprises a series of processing operations from which a product containing the terpene hydrocarbons is obtained. This series of processing operations includes a catalytic cracking step under carefully controlled

conditions, a distillation step to segregate a relatively narrow boiling range fraction, a chemical treating step such as with strong sulfuric acid, and a final distillation step to recover the terpene-rich fraction.

In the catalytic cracking step, specifically a catalytic cracking operation employing the fluid catalyst technique, in which the catalyst flows through the reactor system with the hydrocarbons and is regenerated and reused, it is preferred to employ a synthetic catalyst of the alumina-silica gel type at a temperature of about 950° F. and a pressure of about 5 pounds per square inch; the use of low pressure cracking is recommended for this process since the type olefins resulting in the 85-250° F. fraction are readily converted to terpenes by chemical treatment. The catalytic cracking step may include an operation of the type utilized in the so-called "powdered or fluid catalyst" technique or it may be the commonly called "thermoform catalytic cracking" operation; preferably, the cracking step employs the "powdered catalyst" technique. The conditions of catalytic cracking have been described adequately in the literature and further description of this stage of the process will not be given herein.

In the treating step of the present invention it is preferred to use strong sulfuric acid as the treating reagent. The amount of sulfuric acid employed to contact the catalytically cracked naphtha is important, since, if sufficient amounts of acid are not used, the terpene hydrocarbons will not be formed. Generally, the amount of acid will vary between 5 and 15% by weight based on the catalytically cracked fraction treated. The amount of acid should not be less than the minimum figure given, but larger quantities than the maximum figure may be employed under some circumstances.

The acid treatment is usually conducted at atmospheric temperatures, for example 70° F., but if desired higher temperatures, as in the range of 90° to 150° F., may be used. After the acid treatment has been completed, a sludge is separated from the treated naphtha and either may be reused again or discarded depending on its condition. The treated naphtha is neutralized by treatment with an alkaline reagent and then distilled under conditions of temperature and pressure to segregate a fraction boiling up to about 300° F. which may be used as an aviation gasoline and a fraction boiling between about 300 and 370° F. which contains the terpene hydrocarbons. It is also desirable to segregate a frac-

tion boiling between about 370 and 500° F. which is also rich in alicyclic hydrocarbons.

The terpene fraction obtained in accordance with the present invention has many valuable uses. For example, terpenes may be considered to be derivatives of isoprene which is believed to be the building block of natural rubber. Therefore, the terpene-rich fraction segregated as described may be employed in the production of synthetic rubber. This terpene-rich fraction may be subjected to cracking and dehydrogenation reactions to obtain valuable fractions useful in aviation fuel. Since the high boiling alicyclics (above 370° F.) have unsaturated side chains, these fractions may be employed as base stocks for high quality drying oils. The purified terpene hydrocarbons from the terpene fraction may be used to produce synthetic flavors, deodorants, inhalants, disinfectants and may be used in many other ways too numerous to mention. The terpene-rich fraction may be subjected to further chemical action to produce alcohols, aldehydes and ketones. In short, this fraction may be the starting material for numerous syntheses.

The invention will be further illustrated by reference to the drawing in which the single figure is a flow diagram of a preferred embodiment of my invention. In the drawing the catalytic cracking and chemical treating steps are intended to include all auxiliary separating or settling operations usually associated with catalytic cracking and chemical treating.

Referring now to the drawing, numeral 11 designates a line through which a gas oil, preferably a naphthenic gas oil, is introduced into catalytic cracking stage 12. In catalytic cracking stage 12 suitable conditions for conversion of the gas oil to gasoline in substantial quantities are provided. These conditions have been mentioned before but may include a synthetic type of alumina-silica gel catalyst, temperatures in the range between 900 and 1000° F. and low pressures of the order of 50 pounds or less, preferably about 5 pounds.

After separation of the catalytically cracked product from the catalyst in catalytic cracking stage 12, the hydrocarbons discharge therefrom through line 13 and are injected into distillation zone 14. It is understood that distillation zone 14 may include one or more fractionation towers. In the present instance distillation zone 14 is shown as one fractionation tower. Distillation zone 14 is provided with line 15 for removal of material boiling below about 85° F., line 16 for segregation of a fraction boiling between about 85° and 250° F. and line 17 for withdrawal of heavier constituents which may either be re-cracked or further treated as desired. Distillation zone 14 is also provided with heating means 18 by which temperature and pressure conditions are adjusted to obtain the desired fractionation.

The side stream withdrawn from distillation zone 14 through line 16 is discharged into chemical treating zone 19. Within this treating zone the fraction is contacted with a chemical reagent, such as strong sulfuric acid, which is added to the treating zone by means of inlet 30. The conditions obtaining in chemical treating zone 19 have been described previously herein and further reference to the specific treating operation is not necessary. Suffice to say that the narrow boiling naphtha fraction is intimately contacted with the sulfuric acid under time and temperature conditions such that the desired result is obtained.

The mixture of catalytically cracked naphtha and sulfuric acid is withdrawn from chemical treating zone 19 by way of line 20 and introduced into a separating means, such as a settling vessel 31, where it is allowed to separate under the influence of gravity into a naphtha fraction and an acid sludge fraction. The acid sludge may be removed from vessel 31 by means of outlet 32 controlled by valve 33, and the naphtha fraction is removed from vessel 31 by means of line 34 and introduced thereby into a second distillation zone 21. Similar to distillation zone 14, distillation zone 21 may include several fractionation towers as desired. In the present instance, however, distillation zone 21 is shown as a single fractionating tower provided with line 22 for removal of gasoline hydrocarbons, line 23 for segregation of the terpene-rich fraction, line 24 for segregation of an alicyclic fraction boiling between about 270 and 500° F., and line 25 for discharge of heavier material and alkaline reagent which is introduced into line 34 by opening valve 26 in line 27. The object of introducing alkaline reagent into line 34 is to neutralize any residual acidity in the treated catalytically cracked naphtha fraction and to prevent decomposition of any esters remaining in the treated fraction under the conditions obtaining in distillation zone 21.

Connected to line 24 is line 28 controlled by valve 29. Line 28 connects with line 11 and allows recycling of the alicyclic fraction to catalytic cracking stage 12 whereby this fraction is subjected to catalytic cracking conditions to form additional amounts of gasoline and terpene-rich fractions.

The terpene fraction discharged from distillation zone 21 by line 23 is quite similar to natural turpentine and may be used as a starting point for obtaining the purified terpene hydrocarbons.

The reason for the unexpected result of the present invention in obtaining a terpene-rich fraction is not completely understood. However, it is believed that the catalytic cracking under the conditions mentioned results in the formation of compounds which, on treatment with proper chemical reagents, undergo various chemical reactions such as alkylation, polymerization, isomerization and cyclization such that hydrocarbons of considerably higher boiling point and molecular weight than those originally present in the cracked naphtha fraction are obtained. It is possible that all four of the several types of reactions mentioned occur in chemical treating zone 19 of the present invention. The catalytic cracking operation is one of the essential features of the present invention. Thermal cracking is not equivalent to catalytic cracking in carrying out my improved process. Furthermore, the amount of chemical reagent such as sulfuric acid employed in chemical zone 19 should not be below an irreducible minimum, which figure will necessarily be determined by experimentation since the amount of chemical reagent required in chemical treating zone 19 will necessarily vary with the chemical reagent employed. While no less than 5% by weight of chemical reagent should be employed when strong sulfuric acid is the treating reagent either larger or smaller amounts than this may be used when other treating reagents such as hydrogen fluoride, boron trifluoride, aluminum chloride, or phosphoric acid are substituted for the sulfuric acid.

The boiling range of the catalytically cracked naphtha subjected to the chemical treatment in

chemical treating zone 19 is also important. In general, the fraction subjected to chemical treatment will include the hydrocarbons having 6 carbon atoms in the molecule and those boiling up to about 250° F. Preferably, however, the final boiling point of the fraction treated in accordance with my invention will not exceed about 215° F. for best results.

As an important by-product of the present invention attention is directed to the fraction withdrawn from secondary distillation zone 24 by line 24. This fraction boils between about 370 and 500° F. and contains appreciable amounts of alicyclic hydrocarbons which in themselves may be utilized in many syntheses; or as shown in the preferred embodiment of my invention, this fraction may be recycled to catalytic cracking zone 12 for further conversion into gasoline or terpene-rich fractions.

The present invention will be further illustrated by the following run. A catalytically cracked naphtha fraction boiling between 85 and 215° F. produced by cracking a naphthenic gas oil in the presence of a synthetic alumina-silica gel catalyst at 950° F. and 5 pounds per square inch pressure was acid treated with 15 pounds of strong sulfuric acid per barrel of naphtha fraction. The acid treated oil was neutralized and rerun over a naphthenic soap obtained by introducing caustic into the rerun still in which lubricating oil was being processed. A fraction boiling between 85 and 330° F. was taken overhead from the distillation of the acid treated cracked naphtha and the heavier material was introduced into a vacuum still and distilled under 26 inches of vacuum. The fraction boiling between 340 and 370° F. was found to contain substantial quantities of limonene which has the structural formula

The presence of limonene was deduced from a comparison of the specific gravity and refractive index of the polymer with limonene and turpentine as follows:

Table

	Sp. gr.	R. I.
Fraction boiling between 340 and 370° F.	0.860	1.4799
Limonene	0.860	
Turpentine	0.8617-0.8889	1.4684-1.4818

As a further indication that products obtained in accordance with the present invention belonged to the terpene series, dry hydrogen chloride was bubbled through a terpene oil, produced as described, to obtain a precipitate. The precipitate was removed from the unreacted material and dried and on examination was found to have a decided odor of camphor, indicating the formation of pinene hydrochloride which is artificial camphor.

The terpene-rich oil produced in accordance with the invention was also found to be insoluble in water and soluble in alcohol which is characteristic of the terpenes.

The nature and objects of the present invention having been fully described and illustrated, what I wish to claim as new and useful and to secure by Letters Patent is:

1. A process for producing synthetic turpentine which comprises catalytically cracking a petroleum gas oil under temperature conditions of 900 to 1000° F. and at pressures below about 50 pounds per square inch in the presence of a synthetic alumina-silica gel catalyst, separating from the products of the catalytic cracking a fraction boiling between 85 and 215° F., treating the segregated fraction with 5 to 15% by weight of strong sulfuric acid and distilling the chemically treated product to obtain a gasoline fraction, a terpene rich fraction, and a heavier alicyclic fraction.
  2. A process in accordance with claim 1 in which the heavier alicyclic fraction is recycled to the catalytic cracking step.
  3. A process for producing terpene-type hydrocarbons which comprises the steps of subjecting a petroleum distillate boiling in the gas-oil boiling range to catalytic cracking in the presence of an alumina-silica gel catalyst, separating a fraction boiling above about 85° F. and no higher than 250° F. from the catalytically cracked product, chemically treating said fraction with no less than 5% by weight of strong sulfuric acid and recovering from the chemically treated fraction a product rich in terpenes.
  4. A process for producing terpene-type hydrocarbons which comprises the steps of subjecting a petroleum distillate boiling in the gas-oil boiling range to catalytic cracking in the presence of an alumina-silica gel catalyst, separating a fraction boiling above about 85° F. and no higher than 250° F. from the catalytically cracked product, chemically treating said fraction with from 5 to 15% by weight of strong sulfuric acid and recovering from the chemically treated fraction a product rich in terpenes.

EDWARD FRANK WADLEY.
